HEAT EXCHANGER

Townsend Tinker, Orchard Park, N. Y., assignor
to Ross Heater & Manufacturing Co., Inc., Buf-
falo, N. Y., a corporation of New York

Application March 22, 1947, Serial No. 736,460

6 Claims. (Cl. 257—224)

1

This invention is directed to improvements in heat exchangers of the type which includes an enclosing cylindrical shell and spaced parallel baffle plates formed in adjacency with cutaway portions angularly located whereby the externally flowing liquid or fluid medium travels in a tortuous or sinusoidal path from end to end of the shell.

In such exchangers the external fluid medium flows athwart the tube nest and the efficiency of the heat exchanger corresponds to the flow, quantitatively, of such medium through the spaces between and among the tubes. As a corollary the flow of the external fluid medium in and through the spaces between the tube nest and the shell is substantially without practical effect in the heat exchanging function and, as a result, the efficiency of the exchanger is impaired in degree corresponding to the percentage of the reduction of the volume of the flow of external fluid medium through the spaces between and among the tubes.

This fact has long been recognized and various arrangements have been proposed for the sealing of the spaces between the tube nest and the shell from the path of transverse flow of the external fluid medium, thereby to cause such medium to flow in maximum degree, quantitatively, through the spaces between and among the tubes.

The standard construction of such exchangers is characterized by a base construction which includes a fixed head in which ends of the tubes are secured, baffle plates having openings through which the tubes extend and rods and sleeves as the means for supporting the baffle plates individually and as a series, the rods passing through openings in the baffle plates, having ends secured in the fixed head and free ends carrying nuts or the like which bear upon the adjacent baffle plate, and the sleeves maintaining the proper spacing of the baffle plates and being mounted on the rods.

The prior arrangements proposed for the sealing of the spaces between the tube nest and the shell have the disadvantages of substantially increasing the weight of the exchanger, entailing various special costly and time consuming assembly operations and substantially increasing the cost of manufacture.

The object of the invention is to provide a heat exchanger in which the spaces between the tube nest and the shell are effectively sealed from the path of flow of the external fluid medium through the tube nest by a construction in which the additional weight necessitated by the sealing means

2

is reduced to a minimum, special assembly operations are eliminated and manufacturing cost, in respect to the provision of the sealing means, is reduced to a minimum.

For the accomplishment of this object the invention utilizes the sleeves for the support and spacing of the baffle plates and tubes adjacent the sleeves and provides a construction in which a sleeve carries sealing wing means, the sleeve and the sealing wing means, prior to the assembly of the exchanger, being economically combined as an integer in a relative arrangement such that in the assembly of the exchanger certain tubes adjacent the sleeve will, without special assembly operations, provide a positive lock for suitably holding the sealing wing means against angular displacement from its operative position. In various standard designs of heat exchangers the tie rods are located quite close to the inner circumferential face of the shell and in other standard designs they are located somewhat remote from such face. The invention is applicable in each instance.

In the accompanying drawings:

25 Figure 1 is a partial longitudinal sectional view of a heat exchanger in which the features of the invention are incorporated.

Figure 2 is a cross sectional view on the line 2—2 of Figure 1, looking in the direction of the arrows.

Figure 3 is a fragmentary cross sectional view in the same plane as that of Figure 2 but showing the sealing wing means as consisting of oppositely directed sealing wings.

35 Figure 4 is a perspective view of an integer, applicable to the construction shown in Figures 1 and 2, composed of a sleeve and a single sealing wing.

Figure 5 is a perspective view of an integer, applicable to the construction shown in Figure 3, composed of a sleeve and oppositely directed sealing wings.

The heat exchanger to which the improvement is applicable may be of any well known design 45 characterized by a tube nest, a surrounding shell, transverse baffle plates arranged within the shell and through which the tubes extend, the baffle plates being formed to provide for the sinusoidal flow of the external fluid medium, and tie rods and sleeves for the support and proper spacing of the baffle plates. It will therefore be understood that the particular design shown in the drawing is selected merely for the purpose of exemplification.

50 The form illustrated includes a fixed tube sheet

or head 1 in which the ends of the tubes 2 are secured and a casing 3 below the head 1 which provides the usual inlet and outlet chambers (not shown) for the medium which flows through the tubes 2. The tubes 2 are enclosed in a surrounding shell 4 within which the external fluid medium flows, the shell having adjacent its inner or lower end the usual inlet pipe connection 5 and adjacent its upper or outer end the usual outlet pipe connection (not shown). The tubes 2 are connected at their upper or outer ends to any suitable head, usually a floating head, the illustration of which is deemed unnecessary since such heads, in various forms, are well known standard features of heat exchangers and are shown in many patents of the prior art. The shell 4, head 1 and casing 3 are secured together in any suitable manner, for example, by flanges 6 and 7 at the inner end of the shell 4 and the adjacent end of the casing 3, threaded stems 8 passing through alining openings in the flanges 6 and 7, and nuts 9 upon the projecting ends of the stems 8 and which bear with clamping pressure upon the adjacent faces of the flanges 6 and 7.

The heat exchanger also includes the usual baffle plates 10 arranged in spaced relation in parallel planes normal to the axis of the shell 4 and having opening through which the tubes 2 extend with a close fit in the usual manner. The plates 10 have curved edges which conform to the curvature of the shell, are contiguous to its inner circumferential face, and are interrupted to provide suitable windows 11 through which the external fluid flows. The cutaway of each plate 10 to provide a window 11 is, in the embodiment shown, in the form of a straight transverse edge 12 subtending an arc provided by the curved edge of the plate and of suitably greater than semicircular extent. The windows 11 are arranged in the usual manner at relatively opposite sides of adjacent plates 10 whereby the external fluid medium will flow through the shell in the usual tortuous or sinusoidal path, passing through a window at one side of a lower plate, thence through the nest of tubes 2 and through the oppositely located window in the next upper plate, its flow being continued in this manner until it reaches the outlet (not shown) at the upper or outer end of the shell.

The means for support of the plates 10 includes the usual tie rods 13. These are secured at their lower or inner ends as at 14 in the head 1 and extend through, and have a close fit in, openings provided therefor in the plates 10. The upper ends of the tie rods carry the usual elements (not shown) which bear with clamping pressure against the outer face of the outer or uppermost plate 10 through which the tie rods extend. The tie rods extend through and cooperate with spacing sleeve 15, these being arranged between the several pairs of adjacent baffle plates, the innermost of such sleeves being arranged between the inner or lowermost baffle plate 10 through which the tie rods extend and the head 1. The sleeves 15 serve in the usual manner for the direct support of the baffle plates and the determination of their spacing. The sleeves which are located within the windows 11 will, of course, be twice the length of the sleeves which are located between overlapping portions of adjoining baffle plates.

The tube nest composed of the tubes 2 may have any suitable or standard form and the tubes may have any suitable spacing, according to the

requirements of the particular service for which the heat exchanger may be designed and the particular requirements of the exposed tube area in such service. In the heat exchanger shown the tube nest has the standard generally hexagonal cross sectional outline.

Necessities of design and manufacture require that substantial spaces 16 be left between the shell and the several adjoining tube segments of the perimetric row of tubes. The flow of the external fluid medium through the spaces 16 is a disadvantage in that in such spaces the external fluid medium performs negligible useful work in the exchange of heat with the fluid or liquid flowing through the tubes 2. Thereby the efficiency of the external fluid medium in the heat exchanging function is impaired in proportion to its diversion, quantitatively, into and through the spaces 16, the greater the percent of the medium flowing through such spaces the greater the percent of the reduction of the medium flowing through the spaces between and among the tubes 2 and hence the greater the impairment of the heat exchanging efficiency. The objection is overcome by sealing off the spaces 16 whereby the external fluid medium will flow substantially in its entirety through the spaces between and among the tubes 2.

According to the invention this object is accomplished by utilizing in a unique cooperative capacity the spacing sleeves 15 and adjacent tubes. This cooperative capacity is effected by providing the spacing sleeves with sealing wing means in functional association with adjacent tubes, each sleeve and its associated sealing wing means being originally combined as an integer. Such combination of a sleeve and its associated wing means may be effected in a variety of ways and in an indefinite number of forms embodying the same principles and individually differing merely in details of outline and modes of physical combination of the sleeve and wing means.

In certain designs of heat exchangers, as shown in Figures 1 and 2, the tie rods 13 are located so close to the shell that the sleeves 15 themselves sufficiently seal the space between the tie rods and the shell. In such cases the sealing wing means consists of a single wing 17 carried by the sleeve and projecting inwardly from it, the wing 17 being coextensive in length with the sleeve by which it is carried and, in the generally radial inward direction, having a dimension such that it extends between two adjacent tubes which, depending on the location of the tie rods relatively to the tube nest, may be tubes of the perimetric row or a tube of such row and an adjacent tube of the next innermost row.

Thus Figure 2 shows two wings 17 oppositely located in the space between the overlapping portions of adjacent baffle plates and which extend between tubes of the perimetric row and two other wings 17 oppositely located and which are carried by the sleeves that extend through the windows 11, these latter wings extending between a tube of the perimetric row and an adjacent tube of the next innermost row. It will of course be apparent that at least three tie rods will pass through each baffle plate 10, at least two of which, oppositely located, will pass through the overlapping portions of adjacent plates and the intermediate of which will pass through the window 11 of the next uppermost plate. It will also be obvious that the wings associated with the tie rods which pass through the windows 11 will have twice the length of the wings associated

with the tie rods which pass through the overlapping portions of adjacent baffle plates. In the positions which the wings 17 have with relation to the tubes between which they extend the wings provide positive barriers against the flow of the external medium through the passage constituted by the successive spaces 16; and by the provision of such wings in suitable number with reference to any plane normal to the axes of the sleeves the passages constituted by the several spaces 16 are completely and effectively sealed, throughout the lineal extent of the tube nest, against the flow of the fluid medium whereby such medium will substantially wholly flow through the spaces between and among the tubes 2 and will have the greatest possible efficiency in the heat exchanging function.

In positioning the wings to extend between pairs of adjacent tubes variations in the angles of the planes of the wings to longitudinal diametric planes of the exchanger are necessitated by detail characteristics of the particular design of the heat exchanger. This is illustrated in Figure 2 where the angular positions of the wings at the top and bottom of the figure are different from the angular positions of the wings at the sides of the figure. In assembling the exchanger the wings may be freely positioned in the particular angular relations required because the sleeves 16 by which they are carried are loosely mounted on the tie rods in accordance with standard practice. This freedom of wing positioning in the assembly of the heat exchanger is, however, not permitted to interfere with the permanent retention of the wings in their proper operative positions athwart the spaces 16 because, in such positions, the wings will positively be held against angular displacement about the tie rods as axes by the adjacent tubes between which they extend. Thereby the permanence of the seals provided by the wings is positively insured without the requirement of any special assembly operations and hence without any increment of manufacturing or maintenance cost.

Each wing 17 may be combined with its companion sleeve 15 as an integer in any of various ways. As shown in the drawings the element composed of a sleeve and an associated wing is economically formed by a simple rolling operation as a result of which the wing projects tangentially from the sleeve.

The heat exchanger may have any suitable number of tie rods. Four tie rods, as shown, is the minimum number and is required by most installations. However sundry designs may require more than four tie rods, e. g., six or eight tie rods. The number of wings used to seal off the passage constituted by the spaces 16 should be sufficient in any plane normal to the axes of the tie rods, to achieve the effectiveness of the seal. Where four tie rods are used it is ideal practice to associate the sealing wings with each tie rod. Where more than four tie rods are used, e. g., six or eight, satisfactory results may be obtained in certain cases by limiting the association of the wings to a number of tie rods less than the total number.

Figure 3 shows a design of heat exchanger wherein the tie rods 13 are located at a distance from the inner circumferential face of the shell such that the sleeves 15 will not be effective to seal the intervening spaces. In connection with such heat exchangers each sleeve, as shown in Figures 3 and 5, is provided with an additional wing 17a projecting in a direction opposite to

that in which the wing 17 projects and extending through the spaces between the sleeve and the inner circumferential face of the shell, thereby to prevent the external fluid medium from flowing through such space and to complete the sealing of the space 16.

The double wing and sleeve integer has the same capacity, as above described in connection with the single wing and sleeve integer, for variation of the angular operative positions of the wings 17 in accordance with the locations of the adjacent tubes between which, for the locking function, the wings are to extend. Of course in such variations the wings 17a will have corresponding variations of their angular positions with reference to the inner circumferential face of the shell with resultant variations in the spacing of their straight longitudinal edges from the shell. Such variations of spacing will be without appreciable effect upon the efficiency of the sealing function since the spaces between the straight longitudinal edges of the wings 17a and the shell will, in any event, be so small that the external fluid medium will not flow through them in any appreciable degree.

The element wherein the sleeve is provided with two oppositely directed wings may be made as an integer in various ways. The form shown in Figure 5 is economically fashioned by a simple rolling operation as a result of which the wings project in opposite direction tangentially from the sleeve.

It will be noted that in the construction of the heat exchanger with either form of sleeve and wing integer no special assembly operations are required. The heat exchanger is built up in the ordinary manner, the only requirement being that the spacing sleeves be so positioned with reference to their axes that the wings 17 will extend between the adjacent tubes of an adjacent pair, all as above explained.

I claim:

1. For use as an element of a heat exchanger of the type characterized by a longitudinal nest or tubes, an enclosing shell, spaced baffle plates in diametrical planes of the shell severally formed to provide angularly located adjacent flow windows, inlet and outlet connections for the flow of a fluid medium through the tubes of the nest, inlet and outlet connections for the flow externally of the tubes of a fluid medium which travels in a mean axial direction of the shell through the spaces between adjacent baffle plates and through the windows, a base construction which includes a fixed head in which end portions of the tubes are secured, the tubes passing through openings in the baffle plates, and tie rods secured in said head and located beyond the perimeter of the tube nest through openings in the baffle plates: integers for the support and mutual spacing of the baffle plates and for the sealing of the circumferential space between the tube nest and the shell from the flow of the external medium, whereby such medium will flow substantially wholly through the spaces between and among the tubes comprising the nest, the integers severally consisting of a spacing and supporting sleeve loosely mounted on a tie rod between adjacent baffle plates and associated wing means rigidly carried by and projecting from the sleeve and extending athwart said space between the adjacent tubes of an adjacent pair.
2. For use as an element of a heat exchanger otherwise as set forth in claim 1 but wherein

the tie rods are located closely adjacent the inner circumferential face of the shell: an integer as set forth in claim 1 wherein the supporting sleeve seals the space between the tie rod upon which it is mounted and the shell.

3. For use as an element of a heat exchanger otherwise as set forth in claim 1 but wherein the tie rods are located at a substantial distance from the inner circumferential face of the shell: an integer as set forth in claim 1 wherein the wing means associated with the sleeve consists of oppositely directed wings, one of which extends athwart the space between the tube nest and the shell and between the adjacent tubes of an adjacent pair and the other of which extends athwart said space substantially to the inner circumferential face of the shell.

4. A heat exchanger of the type characterized by a longitudinal nest of tubes, an enclosing shell, spaced baffle plates in diametrical planes of the shell severally formed to provide angularly located adjacent flow windows, inlet and outlet connections for the flow of a fluid medium through the tubes of the nest, inlet and outlet connections for the flow externally of the tubes of a fluid medium which travels in a mean axial direction of the shell through the spaces between adjacent baffle plates and through the windows, a base construction which includes a fixed head in which end portions of the tubes are secured, the tubes passing through opening in the baffle plates, tie rods secured in said head, located adjacent the perimeter of the tube nest and extending through openings in the baffle plates,

and sleeves for the support and spacing of the baffle plates loosely mounted on the tie rods between adjoining baffle plates: wherein the sleeves are provided with rigidly attached wing means which in each instance includes a wing projecting from an associated sleeve athwart the space between the tube nest and the shell and between adjacent tubes of an adjacent pair.

5. A heat exchanger as set forth in claim 4 wherein the sleeves seal the spaces between the tie rods and the shell and are severally provided with a rigidly attached projecting wing which extends athwart the space between the tube nest and the shell and between adjacent tubes of an adjacent pair.

6. A heat exchanger as set forth in claim 4 wherein the wing means consists of wings projecting in opposite directions from the associated sleeve, one of the wings extending athwart the space between the tube nest and the shell and between the adjacent tubes of an adjacent pair and the other extending athwart such space substantially to the inner circumferential face of the shell.
